RAZOR AND DISPENSING MAGAZINE
THEREFOR

Richard F. Landwehr, Laurelton, N. Y., assignor
to American Safety Razor Corporation, Brooklyn, N. Y., a corporation of Virginia

Application February 28, 1950, Serial No. 146,798

15 Claims. (Cl. 30—40)

1

My invention relates generally to a safety razor and more particularly to a razor devised for blade replacement by a dispensing blade magazine; my invention relates generally also to a dispensing magazine and more particularly to a magazine devised for detachable association with a razor for blade replacement.

One of the general objects of the invention is an improved razor of the type wherein a blade is enterable endwise thereinto.

Another general object is the provision in a razor of improved means for locating a blade with its shaving edge in proper relation to the guard.

Another of the general objects of my invention is improved means for holding the blade in shaving position and more particularly of means whereby the blade when so held is given a transverse flexure.

Another general object of my invention is a razor having an improved arrangement for permitting the attachment thereto of a blade magazine for blade replacement.

Another general object of my invention is an improved blade container and coordinately of improved means therein for dispensing a blade therefrom.

A more particular object of the invention is a construction for the attainment of the aforementioned general objects wherein the blades are of the double edged type.

Some of the features of invention for the attainment of the aforementioned and additional objects are these: blade clamping means in the razor which are elevatable to elevate a blade clamped thereby, from a lower level for blade reception to a higher level for shaving performance; means in the path of the blade as it is elevated, to cause the blade to flex transversely; a fixed seat upon which a blade entered into the razor is initially received and a separate blade seat which is elevatable to engage the seated blade and lift it off said fixed seat; a blade seat elevatable to and above the plane of a blade entered into the razor and locating means thereon engageable with the blade before the seat engages and elevates it; fixedly related top and bottom members and blade clamping elements therebetween which are initially movable relatively to each other into adjacency and then movable together relatively to said members to bring the blade into its shaving level; a resiliently biased member in the blade chamber of a razor for exerting pressure on a blade being entered thereinto for engagement by locating

2

means in the razor; a razor head whose blade channel has an entrance mouth capable of receiving both the attaching finger and the ejecting slide of a magazine; a razor whose blade chamber entrance is substantially deeper than blade thickness whereby a blade may be entered at a level above the blade seat to gravitate thereupon; a blade feeding magazine having an attaching finger enterable into a razor to form part of the blade receiving seat in the razor; a blade dispensing magazine attaching finger leveled to and forming a continuation of the bottom wall of the blade discharge mouth; a blade feeding magazine having an attaching finger enterable into the blade receiving chamber of a razor and a guiding member engageable with the razor for leveling the attaching finger to the level of the chamber and more particularly wherein the member levels the finger in advance of its entrance into the razor.

For the attainment of these and such other objects as may hereinafter appear or be pointed out, I have illustrated an embodiment of my invention in the appended drawings, wherein:

Fig. 1 shows a perspective view of the improved razor of this invention.

Fig. 2 shows the razor with its parts separated in an exploded view.

Fig. 3 is an enlarged section taken on line 3—3 of Fig. 1, showing the position of the razor head parts just after insertion of a new blade.

Fig. 4 is a section similar to that of Fig. 3 with the parts of the razor head in their final positions for shaving.

Fig. 5 is an end view of the razor head.

Fig. 6 is an enlarged fragmentary sectional view taken on line 6—6 of Fig. 4, showing parts of certain razor elements in their shaving position with the blade flexed an exaggerated amount.

Fig. 7 is a partial side elevation, showing the razor seated on the lower guiding finger of the improved magazine, preparatory for attachment thereof, and with the guiding finger in longitudinal vertical section.

Fig. 8 is a vertical section taken longitudinally along the center of the mating ends of the razor and magazine, showing the latter in fully attached position, with the topmost blade represented sectionally off center and partially inserted into the razor.

Fig. 9 is a sectional view similar to that shown in Fig. 8 but with the blade fully entered into the razor and with the magazine ejector occupying its most advanced ejecting position.

Fig. 10 is a sectional view taken on line 10—10

55

of Fig. 9 and showing the front of the magazine in elevation except for a portion which is broken away to show the bottom partially in section.

Fig. 11 is a perspective view of my improved magazine partially broken away to reveal inner details.

Fig. 12 is a section through one side of the magazine taken on line 12—12 of Fig. 11.

Fig. 13 is a horizontal section taken on line 13—13 of Fig. 12.

The razor head 12 comprises a hollow frame having a top portion 20 and a bottom portion 30 (see Fig. 1). These portions are preferably formed separately as shown in the exploded view of Fig. 2 because of manufacturing considerations and convenience of assembly. When assembled, they constitute an integrated frame structure with the top and bottom portions in spaced apart relation to provide a chamber within which the blade and the locating and clamping means therefor are receivable in the manner and for functioning as hereinafter to be set forth. It will be understood, of course, that many if not most of the objectives of my invention are attainable even though this frame is made other than of two separate members. For convenience of reference, the top frame portion 20 will hereafter be referred to as the cap and the portion 30 as the razor frame seat.

The cap 20 is shown at the top of Fig. 2 as provided with end walls or flanges 21 and 22, preferably formed integrally with the connecting web portion therebetween.

The means for securing together cap 20 and razor frame seat 30 shown in Fig. 2 comprise lateral extending grooves 23, on the depending end walls 21 and 22, which slidably receive mating projections 33 on the frame seat. The two parts may be secured in this relation as by locking pin 24.

A slot 25 extends through end wall 21 of the cap member and is so dimensioned and positioned to permit ejection of a used, dull blade from the razor. The opposite end wall of the cap is provided with a similar slot 26 to permit insertion of a new blade into the razor chamber. This slot 26 is substantially wider than blade thickness and is further widened centrally, both upwardly and downwardly, by portions 27 and 28 for purposes to be later described. Widened portion 28 is laterally extended by a pair of wedge shaped communicating recesses 29.

The central longitudinal web portion of cap 20, extends for a distance slightly more than the length of a blade and is provided with downward blade engaging abutments 45 at the sides of its inner surface. The under surface is sloped at 47 to permit blade flexing by abutments 45 and is also recessed for its entire length at 41, to receive the spring 42 and the pressure pad or upper clamping member 50.

The razor frame seat 30 has an upper blade receiving and blade ejecting surface 36 which is provided with side flanges 31 serrated to form the razor guard. The blade receiving edge of seat 36 is beveled downwardly as indicated at 37. Through the seat are a number of downward passages 32 which permit egress of soap, lather, shaving cream and the like. A downward extending recess 34, shaped to receive the locator or lower clamping member 70 wholly within its confines, is formed centrally of seat 36. At the blade entrance end of the seat there is formed a channel 35 which extends from the end edge inwardly to communicate with channel 34 and

upwardly to open through blade seating surface 36. At each side of channel 35 is a wedge shaped extension 39 which aligns with slot 29 of the cap. At the bottom and centrally thereof, razor frame seat 30 is provided with a collar 38 whose bore communicates with the bottom of recess 34. The under surface 40 of the razor frame seat 30 extends to meet with the guard edges 31, and is formed flat at the bottom and thence curves upwardly and outwardly on each side in alignment with the bottom edges of cap end walls 21 and 22.

The blade supporting means within the razor head frame preferably comprise a pair of upper and lower clamping members 50 and 70, respectively, and a pressure spring 42 which coact to receive the blade at a lower level in the head and thereafter elevate the blade to an upper level for shaving action. The lower clamping member 70 acts as a supplemental blade seat and clamping member and is rectangular in shape and enlarged in width centrally to conform in configuration to the shape of recess 34. The lower clamping member 70 is provided on its upper surface with the protruding fixed pins 71 which are adapted to be received in the outermost of slots 63 of the blade. Pins 71 are formed with conical or beveled heads having an annular cylindrical surface 72 at the bottom which abuts the end edges of the blade slots 63 when the blade is seated in its final position on the locator. The conical surface facilitates the entrance of the pin into the outermost blade slots 63 and will serve to move the blades to their proper location by wedging action, should they be inserted into the razor slightly off center. The pins 71 are fixedly secured into the locator 70 by any desired means as by force or friction fit. The upper surface 73 of the lower clamping member 70 is convexly curved so that the blade is supported centrally to permit the blade shaving edges to be flexed downwardly. A large orifice 74 extends upwardly through the widened central part of the lower clamping member 70 for reception and attachment of handle parts.

The upper clamping member or pressure pad is a rectangular member provided with openings 51, extending upwardly therethrough to receive the locating pins 71, and a pair of longitudinal lugs 52 which have upward extensions 53 for reception in mating channels 54 defined by shoulders at the ends of channel 41 in the cap 20. These lugs 52 guide the pressure pad vertically with relation to both the cap and the seat. The upper clamping member 50 is preferably formed with a flat under surface for engaging the top surface of the razor blade 60. The upward extensions 53 on lugs 52 serve to space the upper surface of the upper clamping member 50 from the top of the channel 41 at the limit of its upward movement to provide space therebetween for the spring member 42. At least one of the lugs 52 is provided with a blade guiding beveled edge 55.

My improved razor in its preferred embodiment has been constructed to take a double edged blade such as shown at 60. The illustrated blade is provided with cutting edges 61 on each side and a slot 62 at each end for alignment and stacking purposes in the magazine as will shortly be described. In addition a plurality of central locating slots 63 are provided the outermost of which are adapted to receive the locating pins 71 within the razor head. It will be understood that many of the objects of my invention are obtainable

with razors constructed to utilize blades other than that shown and described.

The handle portion 11 of the razor comprises a tapered cylindrical bottom 13 having a vertically fluted peripheral surface to facilitate gripping with the fingers of the hand. A neck 14 extends upwardly from the bottom and to it is rigidly secured a cam section 15 by means of locking pin 16. The cam section 15 comprises a rod shouldered at 17, 18 and 19 to provide sections 81, 82, 84 and 87 of successively smaller diameter. Section 81 is received in an enlarged base at the bottom of collar 38 of the seat. Section 82 is provided with the helical cam slot 83 extending therethrough and flattened at its ends to provide locking action against accidental movement. Cam pin 85 extends entirely through collar 38 and is rigidly secured thereto by force fit of its knurled end portion. The cam pin also extends entirely through section 82 of the handle, riding in the cam slot 83. It will thus be observed that rotation of handle part 13 in one direction will lower rod 15 in collar 38 as shown in Fig. 3 through coaction of the fixed cam pin 85 with the cam slot, while rotation of the handle in the opposite direction will serve to raise the rod in collar 38 to the position shown in Fig. 4. Above the cam section 83 is handle section 84 which is received in a reduced passage at the upper end of the bore of collar 38. Shoulder 19 serves to seat the flat bottom of lower clamping member 70. The lower clamping member 70 is secured to the rod 15 above this shoulder by any desirable means, the preferred means illustrated comprising a washer 86 over which the end portion 87 of rod 15 is peened, in a manner which will permit the lower clamping member 70 to rotate with respect to the rod and yet move linearly in vertical directions by reason of abutment with the shoulder 19 and the walls of recess 34.

When the razor parts described above, and shown in exploded view in Fig. 2, are assembled, the razor will have the appearance illustrated in Fig. 1. It will be observed that the improved razor comprises a head which has spaced upper and lower members 20 and 30 which are fixedly related to define a blade chamber which is open at the sides and provided with a blade ingress aperture in one end and a blade exit aperture at the opposite end. Once a blade has been received into the chamber and seated on the receiving seat 36 as shown in Fig. 3, the blade is securely positioned thereon by pressure downwardly of the upper clamping member 50 and spring member 42. The lower clamping member at this time is seated wholly within recess 34 so that not even the tops of its locating pins 71 are in engagement with the blade. Rotation of the handle 13, by coaction of the cam slot and cam pin, will serve to raise the lower clamping member 70; first to engage pins 71 in blade slot 63 at the outer ends thereof; next to engage the bottom of the blade against the top curved surface of the lower clamping member 70 with the conical portions 72 of the pins 71 extending into the openings 51 of the upper clamping member 50; and finally to lift the blade against the resistance of the upper clamping member 50 to an elevated position in the blade chamber with the upper surface of the blade engaging abutments 45 on the cap 20 adjacent the shaving edges of the blade so as to flex them downwardly in the blade shaving position. In this position the blade edges extend outwardly through the side opening in the blade chamber and the blade is centrally

supported by the lower clamping member 70 at a position higher than the abutments 45 on the cap in the manner shown slightly exaggerated in Fig. 6. At this time the upper clamping member 50 is carried almost wholly within the recess 41 in the cap.

My improved blade holding and feeding magazine 100, shown in Fig. 11 comprises a preferably unitary casing 101 closed on all sides except the rear. The rear is adapted to be closed by member 110 which bears a forwardly projecting platform 111 whose sides are provided with a pair of latching projections 112. These projections are provided with surfaces 113 which are beveled forwardly and upon insertion of the closure into the casing 101 are adapted to spread the side walls thereof, until the detents 113 fall into the vertical latching grooves 102 in the walls. The grooves have surface 103 beveled rearwardly so that removal of the closure will, through action of projection 112, serve again to spread the magazine walls sufficiently to permit removal. The closure member is also provided with vertical lug 114 projecting forwardly therefrom into the space normally occupied by the razor blades. A similar lug 104 is carried by the inner surface of the front wall 105 of the magazine casing. The two lugs 104 and 114 function as aligning means for holding the stack of blades 60 properly aligned within the container, all of the blades except the topmost one being adapted to register their end slots 62 with the aforementioned lugs. The top surface of the magazine container is slotted at 106 from its rear end to a point close to its front side. This slot permits the forward travel of ejector 120, which is provided with a narrowed neck 121 to ride in the slot. A ridged finger manipulating portion 122 is bent forwardly from the neck and slides on the top surface of the container. A similarly shaped, pusher portion 123 is bent forwardly from the neck and biased upwardly toward the under surface of the container top. In the retracted position of the ejector, part 123 sits on or just above platform 111 at the rear of the stacked razor blades, and its side edges seat within the channel defined by a pair of parallel abutments 107 carried for its full length by the under surface of the container top. Pusher part 123 extends below these abutments a distance equal to slightly less than the thickness of one razor blade so that its front edge will engage the rear edge of the topmost blade to eject it from the container. The topmost blade is carried above lugs 114 and 104 by the pressure of spring 124, and its upper surface rests against the under surfaces of abutments 107. When in this position the topmost blade is in alignment with blade ejection slot 125 which extends through the front wall of the container. The upper edge of slot 125 is relieved at the ends and centrally thereof between abutments 107, so as to offer less friction to movement of the blade through the slot, and the widened central portion permits the projection therethrough of pusher part 123 at the forward limit of its advancement. The lower surface of the slot is relieved at the ends for the same reason, and centrally thereof falls into the same plane as the upper surface of lug 104 as well as the upper surface 132 of attaching finger 130. A blade being ejected through the slot is therefore supported at its front by the top of lug 104, the bottom of slot 125 and the top surface of finger 130.

The magazine attaching finger 130 protrudes

forwardly from the front face of container 101, is generally rectangular in shape, and is provided with a pair of wedge shaped lateral projections 131. Finger 130 when inserted into the razor is received in aligned grooves 28 and 35 so that the finger top surface may perform its blade supporting function while the blade is traveling from the magazine into the razor, see Fig. 8. The upper surface 132 of the finger 130 therefore is adapted to form a part or continuation of the blade receiving seat 36, and the wedge shaped lateral projections 131 are received in mating recesses 39 and 29 extending laterally from grooves 35 and 28 so as to prevent upward tilting of the attaching finger 130 in the razor.

Spaced below the attaching finger is a second, guiding finger 140 projecting from the front wall 103 of the magazine. Finger 140 is provided with upwardly flanged side walls 141, and this finger extends forwardly a greater distance from the magazine than does the attaching finger 130. The side walls 141 slope downwardly and inwardly so as to provide a guide surface for the lower part 46 of the razor. In order to attach the magazine in the razor, for purpose of insertion of a new blade, one end of the razor is merely seated on the magazine finger 140 between the side walls 141 as shown in Fig. 7. The magazine and razor may then be pushed toward each other, and attaching finger 130 will be guided by the upper surface of the guiding finger, into opening 28 in the razor. The magazine and razor will then be frictionally secured together and positioned relatively as shown in Figs. 8 and 10.

When thus attached the upper surface 132 of the attaching finger falls slightly above the lower edge of razor entrance passage 26 and slightly below the blade receiving seat 36 in the razor. The pusher 122 may then be advanced manually to start the insertion of a new blade into the razor. At the beginning of such blade movement the forward end of the blade, as it enters slot 26 of the razor, is supported by the magazine finger 130 as previously indicated until its forward edge reaches the beveled portion 37 of the razor receiving seat, see Fig. 8. As blade advancement is continued the forward edge of the blade rides up the beveled portion 37 and engages the beveled surface 55 at the edge of the upper clamping member 50 to be guided onto receiving seat 36 and under the upper clamping member 50. Further advancement of the ejector pushes the blade entirely into the blade chamber of the razor against the resistance of the upper clamping member 50, so that the direction and extent of travel of the blade is limited to that imparted by the pusher. At the limit of its forward motion the pusher extends into slot 27 of the razor cap and the new blade is fully entered, occupying the position shown in Fig. 9 (see also Fig. 3). The blade may now be elevated to its shaving position in the manner previously described.

It will be noted that the widened blade entrance 26 to the razor, the positioning of the blade receiving seat 36 above its lower edge plus the bevels 37 and 55 on the seat and upper clamping member 50 respectively will permit a new blade to find its proper level on seat 36 regardless of the level of its entrance into slot 26. This arrangement has the advantage of permitting relatively large manufacturing tolerances and error in all of the mating parts including the attaching finger while guaranteeing operability of the combined razor and magazine to inject

new and eject old blades. The device is operative for these functions even though under certain manufacturing conditions the upper surface 132 of the attaching finger finds a level above receiving seat 36, for in this case the new blade would still be guided under the upper clamping member 50 and supported at one end between the pad and the magazine finger until elevated by the lower clamping member 70.

It will be understood that the conical shape of the pins 71 enable the latter upon elevation of the lower clamping member 70 to engage the end edges of slot 63 in the razor blade and shift said blade to center it by an amount equal to the radius of the pins, should the blade have been inserted slightly out of center position in the razor chamber.

Having been provided with a blade in the manner described above my improved razor may be utilized for shaving purposes in the normal and conventional manner. If desired the blade may be lowered from its shaving position for rinsing purposes by actuation of the razor handle 13 and during such lowering the blade will be securely grasped between the locator and the upper clamping member, and may be re-elevated to shaving position by merely manipulating the handle again.

When it is desired to replace a dull blade with a new blade the razor is conditioned by rotating the handle to lower the lower clamping member 70 so that the old blade between the two clamping members 70 and 50 is lowered and then held grasped between blade seat 36 and upper clamping member 50 in the manner shown in Fig. 3. The blade magazine 100 may then be attached to the razor and the magazine pusher element 122 manually advanced to force a new blade out of the magazine into the razor in the manner described above. During its movement the forward edge of the new blade as it enters the space between the receiving seat 36 and the upper clamping member 50 engages the rear edge of the used blade. Further advancement of the pusher 45 serves to eject the old blade from slot 25 in the cap as well as advance the new blade. When the old blade is fully ejected and the new blade fully inserted the magazine may be withdrawn from the razor and the new blade elevated to its flexed shaving position substantially as described above.

Having thus described my improved razor and separable attaching blade feeding magazine, it will be obvious that various modifications may be made therein without departing from the scope and spirit of my invention. I therefore do not wish to be restricted to the specific embodiment illustrated and described, preferring rather that my invention be limited only by the scope and spirit of the appended claims.

It will be understood that the magazine 100 may be formed of any preferred or desired material such as plastic, metal or the like.

What I claim is:

1. In a razor head, a blade seat having a depressed central channel, a cap rigidly associated with said seat to define a blade receiving chamber therebetween, a lower clamping member seated in said channel, an upper blade clamping member between the cap and seat biased toward said lower clamping member and manually operable means for elevating said lower clamping member above the surface of said seat.

2. A razor head comprising a frame having a blade receiving seat and a cap spaced there-

above, a blade entrance passage between said cap and seat, an upper clamping member between said cap and seat resiliently biased toward the latter to receive a blade therebetween, a lower clamping member countersunk within said seat and operable to lift a blade bodily from said seat to an elevated shaving position against the pressure of said upper clamping member.

3. A razor comprising upper and lower head members rigidly associated to define a blade passage therebetween, a blade locator countersunk within a recess in said lower member to clear said passage for blade insertion, a handle secured to said frame, and means operable upon manipulation of the handle to lift said locator above said lower member and into said blade passage.

4. A razor head comprising, a frame having an upper cap member and a lower guard member spaced therefrom to define a blade passage, a channel in the lower surface of said cap member for receipt of an upper movable blade clamping member and a channel in the upper surface of said guard member for receipt of a movable lower blade clamping member.

5. A magazine fed razor comprising a cap member and a blade seat member, said cap and seat members being connected in spaced relation to each other by a connecting wall at one end thereof, a blade receiving slot in said connecting wall, said slot having a portion widened downwardly to receive a magazine attaching finger, said blade seat member being provided with a channel, said channel opening into the space between said blade seat and said cap, and said channel communicating at one end with said downwardly widened portion of said blade receiving slot.

6. In a razor, a blade receiving seat having a depressed channel, a cap member rigidly associated with the seat to define a blade receiving chamber therebetween, a blade locator wholly seated in said channel, an upper clamping member between the cap and seat and resiliently biased toward the seat, a wall at one end of said razor having a blade entrance slot therethrough for endwise insertion of a blade past said wall to a receiving position between the seat and the upper clamping member, said upper clamping member being beveled at the end adjacent said wall for guidance of the blade, and means to lift the locator above the surface of said seat.

7. In a razor head, a blade seat having a depressed central channel, a cap rigidly associated with said seat to define a blade receiving chamber therebetween, a lower clamping member seated in said channel, an upper blade clamping member between the cap and seat biased toward said first named clamping member and manually operable means for elevating said lower clamping member above the surface of said seat and for lowering it to clear the blade chamber.

8. A razor having a head comprised of spaced apart top and bottom members rigidly related to provide a passageway therebetween open at both ends and into which a blade may be entered endwise through one open end, the top surface of said bottom member serving as a fixed blade seat to initially receive and seat a blade so entered, and a supplemental blade seat associated with the bottom member for movement upwardly from a lower level wherein it clears the passageway for blade reception and underlies the blade received on the fixed blade seat and manually operable means to elevate said supplemental blade seat above said fixed seat and there-

by lift the blade bodily from off the fixed seat to a higher level wherein its sharpened edges are positioned in shaving relation to the guards.

9. A razor having a frame comprised of spaced apart top and bottom members rigidly related to provide a passageway therebetween open at both ends and into which a blade may be entered endwise through one open end, the top surface of said bottom member serving as a fixed blade seat to initially receive and seat a blade so entered, a pair of clamping members in said passageway mounted for independent movement toward and away from each other and relatively to the frame, one of said members being associated with the frame bottom member for movement upwardly from a lower level wherein it clears the passageway for blade reception and underlies the blade received on the fixed blade seat, and manually operable means for elevating said supplemental blade seat and the seated blade bodily into blade clamping relation to the other clamping member and then additionally elevating both clamping members and the blade engaged therebetween into shaving position.

10. A razor comprising the upper and lower head members rigidly associated to define a blade passage therebetween for seating a blade on the upper surface of the lower member, a blade locator countersunk within a recess in said lower member and elevatable above said seat, and means for elevating said locator to lift a blade bodily upwardly from off the seat to shaving position at a higher level.

11. In a razor, a blade seat having a depressed central channel, a cap rigidly associated with said seat to define a blade receiving chamber therebetween, a lower clamping member seated in said channel, an upper blade clamping member between the cap and seat biased toward said lower clamping member and means in the razor normally operative for maintaining said lower clamping member elevated above the surface of said seat.

12. A razor comprising a frame having a blade receiving seat and a cap spaced thereabove, a blade entrance passage between said cap and seat, an upper clamping member between said cap and seat resiliently biased toward the latter, and means within the razor for elevating the blade bodily from said seat to shaving position against the pressure of said upper clamping member.

13. A razor comprised of spaced apart top and bottom members rigidly related to provide a passageway therebetween into which a blade may be entered endwise through one end of the head and provided with guards for the shaving edges, the top surface of said bottom member serving as a fixed blade seat to initially receive and seat a blade so entered, and a supplemental blade seat associated with the bottom member for movement upwardly from a lower level wherein it clears the passageway for blade reception and underlies the blade received on the fixed blade seat and means to elevate said supplemental blade seat above said fixed seat and thereby lift the blade bodily from off the fixed seat to a higher level wherein its sharpened edges are positioned in shaving relation to the guards.

14. In a razor, a blade seat having a depressed central channel, a cap rigidly associated with said seat to define a blade receiving chamber therebetween, a lower clamping member seated in said channel, an upper blade clamping member between the cap and seat biased toward said first

11

named clamping member and means for elevating said lower clamping member above the surface of said seat and for lowering it below said surface.

15. A razor head comprising a frame having a blade receiving seat and a cap rigidly associated therewith and spaced thereabove, a blade entrance passage between said cap and seat, a blade-clamping member countersunk within said seat, and operable to lift a blade bodily from off said seat to an elevated shaving position against said cap.
